UNITED STATES PATENT OFFICE.

DAVID C. STEPHENSON, OF TOLEDO, OHIO, ASSIGNOR TO THE NATIONAL MALLEABLE CASTINGS COMPANY.

RAIL-JOINT.

1,145,336.

Specification of Letters Patent.

Patented July 6, 1915.

Application filed May 8, 1913. Serial No. 766,262.

To all whom it may concern:

Be it known that I, DAVID C. STEPHENSON, a citizen of the United States, residing at Toledo, Lucas county, Ohio, have invented new and useful Improvements in Rail-Joints, of which the following is a specification, reference being had to the accompanying drawings, in which—

Figure 1 is a plan of my improved joint 10 showing one of the rails in section; Fig. 2 is an end elevation thereof; Fig. 3 is a section partly in elevation on lines III—III of Fig. 1; Fig. 4 is a section on lines IV—IV of Fig. 1; Fig. 5 is a detail of one of the 15 rail engaging members; Fig. 6 is a plan of a modified form of my device; Fig. 7 is an end elevation thereof; Fig. 8 is a section on lines VIII—VIII of Fig. 6, Fig. 9 is a section on lines IX—IX of Fig. 8; Fig. 10 is a plan partly in section of a further modification and Fig. 11 is an elevation thereof.

My invention relates to rail joints and consists in a joint which eliminates the necessity of using bolts for securing the fastening means to the rails, and provides a structure of great strength and simplicity.

My invention also consists in the construction and arrangement of parts which I shall hereinafter describe and claim.

Referring to the drawings; the numeral 2 designates end portions of adjacent rails, 3 the usual cross-ties, and 4 the base or joint plate preferably located between the ties. The joint plate 4 is preferably symmetrical in cross-section, is of uniform cross-section throughout its length and has upturned sides 5, 5'. The rail engaging member 6, which extends across the joint, is adapted to have a supporting engagement with the heads 7 of the rails, and its portion 8 bears against the undercut inner face of the side 5 of the plate and against the upper faces of the flanges 9 of the rails. The member 6 has a shoulder 10 adapted to overlie the upturned side 5 of the plate 4. The member 6 also has lugs 11 which overlap the ends of the joint plate and prevent relative longitudinal movement of the plate 4 and the rail engaging member 6. On the opposite side of the rails is another rail engaging member 12 which extends across the joint and engages the rails between their flanges 9' and the heads 7. The rear faces 13 of the member 12 incline 55 outwardly from the ends toward the center

of the member, and between these inclined faces 13 is a rearwardly extending projection 14 having curved deflecting channels 15 therein. The undercut face 16 of the side 5' of the joint plate 4 lies parallel with the longitudinal axis of the rail, and between the faces 16 of the side 5' and the inclined rear faces 13 of the member 12 are wedges 17, the inner and outer faces of which correspond to the faces 16 and 13 respectively. The wedges 17 have on their under sides slots 18 for the reception of the bendable key members 19, the ends of which are adapted to be driven into the deflecting channels 15 in the member 12. The keys 19 are provided with driving heads 20.

To prevent longitudinal movement of the joint as a whole relative to the rails, bosses 21 may be provided on a rail engaging member suitable for insertion into the bolt holes 75 in the rail webs, which are normally used in connection with the ordinary fish-plate joints, or the flanges of the rail may be cut away at 22 for the reception of an angular lug 23 on a rail engaging member.

Clearance spaces are provided between the shoulders 10 on the member 6, and the side 5, and also between the upper faces of the wedges 17 and the shoulders 24 of the member 12 to permit these parts to adjust 85 themselves to variations in the size of the rails and of the parts of the rail joint.

My device is applied to the rail in the following manner: I place the joint plate 4 under the ends of the two rails to be joined 90 in such position that it will extend longitudinally an equal distance each side of the joint. I then insert the rail engaging member 6 with its portion 8 extending into the V-shaped space between the flanges 9 of the rail and the upturned side 5 of the joint plate, and with its shoulder 10 overlying the upper edge of the side 5 and with the lugs 11 engaging the ends of the joint plate. I next insert the other rail engaging member 12 in position against the opposite side of the rail with the bosses 21 in the bolt holes, or if the bosses are not used with the lug 23 in the angularly shaped recess 22, and drive the wedge members 17 toward each other between the faces 13 of the member 12 and the face 16 of the side 5' of the joint plate until the wedges 17 have forced the plate, the rails and the rail engaging members into solid engagement with each other.

The bendable key members 19 are inserted into the slots 18 and are driven longitudinally so that their tapered ends will lock in the deflecting channels 15 until the heads 20 come into engagement with the outer ends of the wedges 17, in which position they hold the wedges securely against the side 5' of the joint plate and the inclined faces 13' of the rail engaging member 12.

10 In Figs. 6, 7, 8 and 9 I have shown a modification of my invention in which I use only one bendable key member 19' for locking the wedges 17' in the position into which they have been driven. In this form the key 19' is inserted in a slot 18' and is driven into a curved deflecting channel 15' in the other wedge 17', thereby locking the wedges in driven position between the undercut face 16' of the plate 4' and the inclined faces 13' 20 of the rail engaging member 12'.

In Figs. 10 and 11 I have shown a further modification of my invention in which the wedges 17² are locked in position by the bendable key members 19² which are driven 25 longitudinally in slots 18² in the inner side faces of the wedges 17² and deflecting channels 15² in the faces 13² of the member 12². In this modification the rail engaging member 12² has a rearwardly and downwardly 30 extending boss 25 which engages a recess 26 in the plate 4² and prevents movement of the member 12² relative to the plate 4².

It is obvious that various modifications 35 may be made in the constructions which I have shown and described herein without departing from my invention.

What I claim is:

1. A rail joint comprising a base member 40 of rolled or forged material having a cross section which is substantially uniform throughout its length, and having upturned sides parallel with the web of the rail, rail-gripping members extending across the joint, an incline on one of said rail-gripping 45 members, wedging means adapted to be driven between said incline and an upturned side of the base plate, and bendable locking means for holding the wedging means in position.

50 2. A rail joint comprising a base member having upturned sides and being of substantially uniform cross section throughout its length, rail-gripping members extending across the joint, wedging means adapted to be driven between one of said rail-gripping 55 members and an upturned side of the base member, and means adapted to be bent and locked in a curved guideway in said rail-engaging members to lock the wedging means.

60 3. A rail joint, comprising a joint plate of substantially uniform cross-section throughout its length, the sides of the plate having their inner faces parallel with the web of the

65 rail, rail gripping parts adapted to bear against the flanges of the rails and support the rail heads, wedging means adapted to be driven longitudinally of the rail between a side of the plate and one of said rail gripping parts, bendable locking means cooperating with the wedging means and with the 70 said rail gripping part for locking the wedge in driven position.

4. A rail joint, comprising a joint plate of substantially uniform cross section throughout its length, rail gripping parts adapted to 75 engage the rails between their heads and base flanges, wedges adapted to be driven longitudinally of the rail between one of said rail gripping parts and a side of the 80 joint plate, the said rail gripping part having therein curved deflecting channels, and bendable key members co-operating with said curved deflecting channels for locking the wedges in driven position.

5. A rail joint, comprising a joint plate of 85 substantially uniform cross section throughout its length, rail gripping parts adapted to bear against the flanges of the rails and support the rail heads, wedging means operating between a side of the plate and one of 90 the rail gripping parts, the said rail gripping part having a projection thereon adapted to engage a recess in the base flange of the rail, and bendable locking means co-operating with curved deflecting channels in 95 a rail-gripping part for locking the wedging means in driven position.

6. A rail joint, comprising a joint plate, rail gripping parts adapted to bear against the flanges of the rails and support the rail 100 heads, one of said rail gripping parts having on its rear side wedging faces inclined longitudinally from its middle portion to its ends toward the rails, wedges adapted to be driven longitudinally of the rails between a 105 side of the plate and the said inclined wedging faces, and bendable locking means for locking the wedges in driven position between the side of the plate and said inclined faces of a rail gripping part.

110 7. A rail joint, comprising a joint plate of substantially uniform section throughout its length, extending beneath the rails, and having upturned sides, rail engaging members lying between said upturned sides and the rails, one of said rail engaging members having an incline on its outer surface, a wedge co-operating with said incline and with a longitudinally extending side of the joint plate 115 and adapted to clamp the parts to the rails, and means for locking the wedge in wedging 120 position.
